[57] **CLAIM**

The ornamental design for a holder for coffee filters, as
shown and described.

DESCRIPTION

FIG. 1 is a front elevational view of the holder for
coffee filters showing my new design;

FIG. 2 is a rear elevational view thereof;

FIG. 3 is a top plan view thereof;

FIG. 4 is a bottom plan view thereof;

FIG. 5 is a left side elevational view thereof, the oppo-
site side being identical;

FIG. 6 is a front elevational view of an alternate em-
bodiment of FIG. 1 on a reduced scale, the coffee maker
shown in broken lines for illustrative purposes only;

FIG. 7 is a front elevational view of FIG. 6;

FIG. 8 is a rear elevational view of FIG. 6;

FIG. 9 is a top plan view of FIG. 6;

FIG. 10 is a bottom plan view of FIG. 6; and,

FIG. 11 is a left side elevational view of FIG. 6, the
opposite side being identical.
